United States Patent Office.

GUSTAV L. JAEGER, OF NEW YORK, N. Y.

Letters Patent No. 92,831, dated July 20, 1869; antedated June 7, 1869.

IMPROVED PAPER BOX.

The Schedule referred to in these Letters Patent and making part of the same.

To all whom it may concern:

Be it known that I, GUSTAV L. JAEGER, of the city, county, and State of New York, have invented a new and useful Improvement in Paper Boxes; and I do hereby declare the following to be a full, clear, and exact description thereof, which will enable those skilled in the art to make and use the same; reference being had to the accompanying drawing, forming part of this specification, in which drawing—

Figure 1 represents a vertical central section of this invention.

Figure 2 is a horizontal section of the same.

Similar letters indicate corresponding parts.

This invention consists in the arrangement of an outwardly-projecting flange on the body of a paper box, or of its cover, said flange being produced by stamping, pressing, spinning, or otherwise, and being made equal in diameter or circumference to that of the head, to be applied to said body in such a manner, that said flange serves as a guide to bring the body in the correct position in relation to the head; and, furthermore, it affords a good hold for the trimming, which serves to unite the body and the head, and which may be of paper, muslin, thin sheet-metal, or any other suitable material.

In the drawing, the letter A designates the body of a paper box, or of its cover, which may be round, oval, square, or of any other desirable form or shape.

This body is provided with an outwardly-projecting flange, *a*, which is produced, by preference, after the

ends of said body have been united, and which may be produced, either by stamping, pressing, spinning, or by any other suitable means.

If the body A is round, I produce the flange while the body is being cut off, by an operation similar to spinning.

The outside diameter or circumference of the flange *a*, I make equal to that of the head, B, which is to be attached to the body A, so that by said flange a guide is obtained, whereby the body can be brought readily in the proper position in relation to the head.

After the body has been placed on the head, these two parts are united by a trimming, *b*, which may consist of paper or muslin, and fastened by paste or glue, or which may be of thin sheet-metal, and simply fastened by pressing the same over the edge of the head, and over the flange.

By means of the flange, the body A and the head, B, can be readily and firmly united, and handsome boxes can be produced with little trouble or expense.

Having thus described my invention,

What I claim as new, and desire to secure by Letters Patent, is—

The arrangement of an outwardly-projecting flange, *a*, on the body A of a paper box, substantially as shown and described.

GUSTAV L. JAEGER.
